DESIGN FOR A DRESS

Phyllis Byrnes, New York, N. Y.

Application January 26, 1939, Serial No. 82,608

Term of patent 3½ years

To all whom it may concern:

Be it known that I, Phyllis Byrnes, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the specific dress disclosed of the specific, bow-trimmed bands of stiffened self-fabric arranged on the sleeves and on the skirt as shown.

I claim:

The ornamental design for a dress, substantially as shown and described.

PHYLLIS BYRNES.
